VENTILATING WINDOW SHADE

Oscar P. Cadmus, New York, N. Y.

Application November 17, 1934, Serial No. 753,532

4 Claims. (Cl. 156—10)

This invention relates to a window shade which is designed and adapted for shading disposition, or to be drawn down in relation to the window opening, yet admitting air therethrough to a room 5 or apartment, when a sash of the window is in an open or partly open position.

The invention consists of the features herein-after described by which a window shade will serve as a ventilator and at the same time give an 10 ornamental appearance to the shade.

The nature of the invention and its distinguishing features and advantages will appear when the following specification is read in connection with the accompanying drawing, in which

15 Fig. 1 is an inside view of a window, showing a roller shade embodying the invention arranged in the window opening, the lower sash being shown raised to admit air which passes through the shade, a portion of the shade being broken 20 away to show the raised sash.

Fig. 2 is an enlarged inside view of a portion of the shade showing more clearly certain features of the ventilating means.

Fig. 3 is an enlarged section on the line 3—3 25 of Fig. 2.

Fig. 4 is an enlarged section on the line 4—4 of Fig. 2.

Figs. 5 and 6 are views similar to Fig. 2 showing 30 modifications.

35 On reference to Figs. 1 to 4 inclusive, it will be apparent that there is shown a shade 10 which is made of suitable material, such as oil opaque cambric or other cloth; the shade being wound on and unwound from the usual spring roller 11 mounted in the frame of a window 12 at the head 40 rail thereof. The shade 10 is thus mounted for shading disposition, or to be drawn down in relation to the window opening, as shown in Fig. 1. The shade has the usual pull slat in a hem on the lower end thereof.

In accordance with the invention the shade 10 has an apertured area for the passage of air therethrough, and means to cover the apertured area, but without preventing the passage of the air 45 through said area. In the present instance the apertured area is at the lower end of the shade 10, and consists in the provision of a plurality of apertures 13 in the shade. The apertures may be of any shape, and are arranged in spaced rows 50 transversely of the shade. There are five rows of apertures in the present instance, but any number of rows may be provided. The means for covering the apertured area in the present instance consists of strips 14 of the same material 55 as that of the shade, there being one strip 14 for

each row of apertures 13. The strips 14 are secured to the shade on the inside thereof by lines of stitching 15 and 16 respectively, occurring at the top and opposite ends of the apertures, and leaving the lower edges of the strips 14 unsecured. 5 Due to the flexible nature of the strips they may be distended as shown in Fig. 3, thereby permitting air to pass through the apertures 13. The air will be deflected downwardly by the strips, and for this reason serve as deflectors or baffles. 10 The strips are scalloped to conform to the shape of the apertures and give an ornamental appearance. It is obvious that the strips will not interfere with the rolling or winding of the shade because of their flexible nature.

15 In Figs. 5 and 6 there are shown variations in the shapes of the apertures and strips, to indicate that various ornamental effects may be obtained within the invention, aside from providing desired ventilation.

20 From the foregoing it will be understood that when the shade having the features described is down in a shading disposition, with the lower window sash raised, as shown in Fig. 1, an amount of fresh air, greater than the amount ordinarily 25 admitted, is permitted to flow into a room or apartment, by reason of the apertures 13, while the appearance of the shade is embellished by reason of the apertures and strips.

I claim:

30 1. A window shade having a plurality of apertures for the passage of air, and means on said shade individual to each aperture covering the aperture without preventing passage of the air therethrough.

35 2. A window shade having a plurality of apertures for the passage of air, and means on said shade individual to each aperture including material similar to that of the shade covering the aperture without preventing passage of the air 40 therethrough.

45 3. A window shade having rows of ventilating apertures for the passage of air, and a strip of ornamental design for each of said rows on the shade covering the apertures without preventing 45 passage of the air therethrough.

50 4. A window shade having rows of ventilating apertures for the passage of air, and a flexible strip for each of said rows secured to the shade covering the apertures without preventing passage of the air therethrough, said strip being secured to the shade by lines of stitching along one side and the opposite ends of each aperture.
